SUPERMARKET SHOPPING CART

Alex M. Parker, 793 Howard Court E., Oradell, N.J.

Filed Mar. 15, 1965, Ser. No. 84,267

Term of patent 14 years

(Cl. D14—3)

FIG. 1

FIG. 2

The dominant features of my design reside in the portions shown in full lines.

I claim:

The ornamental design for a supermarket shopping cart, substantially as shown and described.
